UNITED STATES PATENT OFFICE.

MARK THOMAS DENNE, OF LONDON, ENGLAND.

BED-LASTING MACHINE.

Application filed July 5, 1924. Serial No. 724,480.

To all whom it may concern:

Be it known that I, MARK THOMAS DENNE, a subject of the King of England, residing at London, W. 1, England, have invented 5 new and useful Improvements in Bed-Lasting Machines, of which the following is a specification.

This invention has reference to improvements in and relating to bed-lasting machines and is concerned more particularly with means for operating the heel pad or clamp.

The main object of my invention is to provide a toe-lasting machine with a heel 15 pad actuating means that will greatly facilitate and expedite the clamping and unclamping of the shoe; and which may be made so as to leave the operator's both hands free for positioning, adjusting or removing the shoe, thereby saving time.

In accordance with an important feature 20 of my invention I provide a bed-lasting machine with a heel clamp that is under complete control, to clamp or unclamp the work, by the operator's merely operating a pedal lever. The heel clamp may be actuated automatically in one direction—for instance in the direction to clamp the heel—and moved in the opposite direction by the operator's 25 depressing the treadle. Further, the mechanism may be such that the automatic means actuate the heel pad in one direction against the action of a spring that tends to move the pad in the opposite direction, the treadle 30 lever in such case merely reversing or throwing out of action the automatic means and thereby permitting the spring referred to 35 to move, for instance to retract, the heel pad.

By the use of means operating about as 40 indicated, the operator need depress the treadle only at the time he is placing the shoe in and at the time he is removing the shoe from the machine. Further, the moment he has properly positioned the shoe— 45 for which purpose both his hands are required—he releases the treadle and the shoe is at once clamped. Similarly, when the shoe is lasted he grasps it with both hands and simultaneously depresses the treadle so 50 that the shoe is at once free to be removed.

The means whereby the heel pad is moved so as to clamp the shoe, may be of such a character that whilst it will adapt itself even to the slightest variations in the work 55 (for instance one shoe upper may be thicker than another), it will nevertheless preclude

the possibility of the shoe being moved rearwardly by any pressure brought to bear when the toe is being lasted.

I propose to describe, by way of example, 60 a preferred constructional form of my invention but I wish it to be understood that the scope of my invention is not limited to that particular form.

In the accompanying drawing Fig. 1 65 shows my invention in front elevation and Fig. 2 is a right hand side view partly in section of the means for imparting movement in one direction to the heel pad.

In said drawing the character A indicates 70 the usual slide that supports or is provided with the jack frame 8. The slide is adjustable on bearings in the base of the machine, for instance by screw and hand-wheel, to set the apparatus at least approximately to suit 75 different lengths of shoes. These parts being well known are not further described.

The heel clamp 1, of any suitable construction, is secured by screws 2 to the end of a sliding head 3 which, in turn, is 80 secured to the spindle 4 by screw 5 and washer 6.

The spindle 4 is supported so as to be 85 slideable in a bearing in a carriage 7 that is carried on segmental rails on the jack frame 8, means being provided to clamp the carriage after being set up or down on its support to suit different shapes of lasts.

The carriage 7 has a projection 7^a on which the head 3 slides and by which the 90 spindle 4 and heel pad 1 are held against rotation.

Attached to the carriage 7 is a bracket that is formed or provided with a cylindrical chamber 9 that extends at right angles 95 with respect to the spindle 4 and into which chamber the right hand end of the said spindle projects.

Supported in bearings at the ends of the chamber 9 is a second spindle marked 12, 100 on one end of which a snail cam 11 is fixed and against which the spindle 4 is held by a spring or springs 10. It will be seen that by rotating the spindle in one direction the snail cam will permit the springs 10 to move 105 the heel pad away from the last, i. e., to the right in Fig. 1, whereas when rotated in the opposite direction the snail cam will force the spindle and pad towards the left and against the last or shoe.

Secured at one end to the casing or chamber 9 and at the other to the spindle 12 is

a spring 13 that is under considerable tension and which normally maintains the spindle 12 so that the snail cam 11 maintains the heel pad in its most advanced position.

5 The longitudinal axis of the spindle 4 is in the plane in which the axis of the cam 11 lies so that to whatever position the snail cam be rotated it will offer a positive resistance to the movement of the spindle 4 and heel 10 pad 1 by pressure on said pad.

By the arrangement of the snail cam as described and by reason of the fairly powerful action of the coil spring 13, the pad will be made to press with a very firm pressure 15 against the shoe and it will not permit any retrograde movement of the shoe no matter what pressure be brought to bear during the operation of lasting the toe.

To prevent overrunning of the snail cam, 20 a stop 21 is provided that comes against the spindle 4 (or a step cut therein) when the cam has moved the pad to the extreme advanced position.

Secured to the other end of the spindle 25 12 (which projects outside the chamber 9) is a drum 14, it being shown secured to the spindle by a set screw having an extension 15 to form a handle and attached to the drum is a chain 16 the other end of which 30 is secured in an adjustable manner to a lever 17 which is fixed on a pedal shaft 18 having a pedal lever 19 secured at a position convenient to the workman.

As shown the chain 16 passes over a roll 35 on the lever 17 and its end is provided with a hook 20 to be engaged with one or other of the link pins of the chain so that the effective length of the latter may be adjusted accordingly as the carriage 7 is set up or 40 down on the jack frame 8.

The operation is as follows: The operator, having hold of the shoe with both hands, depresses the treadle 19. Through the chain 16 the spindle 12 and snail cam 11 are rotated in opposition to the tension of 45 the coil spring 13. This at once permits the sliding spindle 4 and the heel pad 1 to be moved, by the spring or springs 10, to make room for the shoe being placed in position 50 on its supports. The moment the shoe is

properly placed, and before, possibly, he lets go of the shoe, the operator releases the treadle, and the snail will instantly rotate and cause the heel pad to be pressed with considerable force against the heel, thereby 55 firmly clamping the shoe in position.

When the lasting has been completed, the operator grasps the shoe with both hands, and simultaneously depresses the treadle, when the shoe may at once be removed. 60

The handle 15 is provided for emergency use as the main object of the invention is to provide heel pad operating mechanism by the use of which the workman's both hands are left free to handle the work. 65

What I claim is:—

1. A pedal controlled heel pad in which the heel pad is carried by a slideable but non-rotatable spindle, a spring tending to move the spindle in a direction away from its most advanced position and a spring operated device whereby the spindle and pad are normally held in their most advanced position. 70

2. In a bed-lasting machine a pedal controlled heel pad having in combination a non-rotatable slideable spindle, a second spindle at an angle with respect to the first, and adapted to be rocked, a snail cam on the second spindle arranged to contact with the end of the first, a spring tending to rotate the snail cam and its spindle in the direction to move the heel pad against the last, a stop to prevent overrunning of the snail cam and a connection actuated by a treadle 75 to rotate the snail cam so as to permit the heel pad to move away from the last. 80

3. In a bed-lasting machine a heel pad operating mechanism having in combination, automatically acting means to move the heel pad against the last and to lock the pad against retrograde movement, a pedal actuated device to operate said means in the direction to bring about the releasing of the last, and other automatically acting means 90 whereby the pad will be moved away from the last after the pedal actuated means have been operated, substantially as set forth. 95

MARK THOMAS DENNE.
